Primary Examiner — Melanie H Tung(74) *Attorney, Agent, or Firm* — Mintz Levin Cohn Ferris Glovsky and Popeo, P.C.(57) **CLAIM**

The ornamental design for a display screen with an icon, as shown and described.

DESCRIPTION

FIG. 1 is a front view of a display screen with an icon; and, FIG. 2 is a front view of a second embodiment thereof. The broken line showing in both views forms no part of the claimed design.

Graphic display of electrocardiogram (ECG) data, such ST segment elevation/depression, in form of an icon on a display screen during a medical evaluation or procedure.

1 Claim, 2 Drawing Sheets(56)
